UNITED STATES PATENT OFFICE.

FREDERICK W. HEDGELAND, OF CHICAGO, ILLINOIS.

DESIGN FOR A LAMP-BODY.

SPECIFICATION forming part of Design No. 31,887, dated November 28, 1899.

Application filed November 4, 1899. Serial No. 735,838. Term of patent 14 years.

To all whom it may concern.

Be it known that I, FREDERICK W. HEDGELAND, a citizen of the United States, residing at Chicago, in the county of Cook and State 5 of Illinois, have invented and produced a new and original Design for a Lamp-Body; and I do hereby declare the following to be a full, clear, and exact description of the same, reference being had to the accompanying drawing, forming a part of this specification.

The drawing is a view in perspective of a lamp-body, showing my design and fully illustrates the invention.

15 The leading feature of my design consists of the cylindrical body A, having the annular sloping shoulder B contracting into the

cylindrical neck part C, which is of a less diameter than that of the body A. The neck part ends in the flat top a, in which is inserted the lower end of a burner-tube D. The lamp-body is provided near its longitudinal center with an annular bead b, and at the lower end it is provided with a shoulder-ring d, and below this ring with a bead g. 20 25

What I claim is—

The design for a lamp-body, as herein shown and described.

In testimony whereof I affix my signature in presence of two witnesses.

FREDERICK W. HEDGELAND.

Witnesses:

L. M. FREEMAN,
L. B. COUPLAND.
